UNITED STATES PATENT OFFICE.

WILLIAM A. JONES, OF SHARON, AND WILLIAM A. MINEHAN, OF SHARPSVILLE, PENNSYLVANIA.

LOCOMOTIVE ATTACHMENT.

1,078,624.

Specification of Letters Patent.

Patented Nov. 18, 1913.

Application filed December 19, 1910. Serial No. 598,207.

To all whom it may concern:

Be it known that we, WILLIAM A. JONES and WILLIAM A. MINEHAN, citizens of the United States, residing at Sharon and Sharpsville, respectively, in the county of Mercer and State of Pennsylvania, have invented certain new and useful Improvements in Locomotive Attachments, of which the following is a specification.

10 Our invention relates to improvements in a locomotive attachment and is directed particularly to an improvement on such an attachment, for example, as shown in U. S. Patent No. 975,870, heretofore granted to us 15 November 15th, 1910.

In practice, we have found that in the use of such an attachment as is shown and described in the United States patent above referred to, unless the steam is carefully regulated by the hand valve in the attachment, 20 the following undesirable results occur, viz., when the attachment is being used for melting alone, a sudden or heavy pressure of steam will, under certain conditions, create 25 an eddy in the suction chamber and a resulting back pressure on the steam hose which is undesirable, while in the use of the attachment to throw out the water, the steam valve must be opened gradually to admit of priming. These features both require 30 time and experience in operation, and an effort to overcome these difficulties and provide an attachment which may require no 35 nicety of operation, and may be used with like results by the experienced and inexperienced, has inspired the present invention.

One of the objects of our invention is the combination in an attachment for locomotives of means for melting the snow and ice 40 from frozen switches and switch levers and of means for carrying away the water resulting from the melting of ice and snow so that it may not refreeze in the switches.

Another object of our invention is the provision of such an attachment in which steam coming from the locomotive may be directed 45 against the frozen switch or switch levers, or sent through a by-pass to act as a water siphon.

50 A still further object is the construction of such an attachment in which a full head

of steam may be at once sent through a by-pass and which is self-priming at the commencement of the siphoning.

A still further object is the equipment of 55 such an attachment with a guard for preventing stones and earth being thrown back upon the operator by the steam pressure.

Still further objects and purposes of our 60 invention will appear from an inspection of the drawing, the specification describing the same, and the claims appended thereto, in which are set forth the combination of elements, arrangement of parts, and novel structural details properly comprised within the 65 same.

In the drawing in which is shown a preferred construction of our invention, Figure 1 is a view of the standard type railway locomotive and tender showing the piping 70 leading from the upper rear portion of the locomotive boiler adjacent the steam dome to points on the engine and tender to which the attachment shall be connected. Fig. 2 is a general view of our attachment showing only 75 a fragment of the steam hose for connection to the engine piping. Fig. 3 is a longitudinal sectional view of the attachment as shown in Fig. 2 on a somewhat larger scale.

Referring now to the several figures in 80 which like reference characters designate like parts, (1) represents a locomotive and tender, (2) is a pipe leading from the rear of the steam dome and terminating, in the present instance, at a plurality of points (4) 85 in the forward part of the locomotive and at the rear of the tender. The tender piping is connected to the locomotive by standard steam hose (2'). A valve, not shown, located in the engineer's cab, is used to regulate the pressure of steam flowing through the piping. Adjacent to each terminus of the piping, we provide valves (3) by means of which the operator of our attachment may 90 regulate the flow of steam into the attachment. In connecting the flexible steam hose (6) to the piping (2) at (4) we use a standard coupling (5). The steam hose is suitably secured and connected at its other end to a short pipe (7) which is threaded into 95 a three way valve (8) having an operating handle (8') therein. Extending in line with 100

pipe (7) are the pipes (9 and 11) and the union (10), pipe (11) being threaded into the Y 12. Continuing from Y 12 and in line with pipes (7, 9 and 11) is the pipe (13) on which is adjustably mounted a semi-circular shield (14) provided with a set screw (14'). Extending from the three-way valve (8) at right angles to the pipes (7 and 9) is the pipe (15) bending at right angles to itself and provided with the reducer (16). Connecting the reducer and the bushing (17) is the nozzle (20) passing through and terminating at the forward end of the suction chamber (18), this nozzle being reduced at its forward end as shown at 20'. The suction chamber, which is properly a T-fitting, is provided at its lower aperture with a member (19) perforated as at 19'. Continuing from the forward part of the suction chamber (18) is the pipe (21) bent approximately 45 degrees and threaded into the hand valve (22). Connecting the other end of this valve and the other branch of the Y 12 is a short pipe (23).

It must be understood that, exclusive of the elements 14, 14', 16, 17, 19, and 20, all of the elements from 7 to 23 may be standard pipe fittings.

In operation, our attachment is coupled to the piping, and steam being admitted into the pipe (2), the steam pressure in the attachment is regulated by a valve at 3 so as to throw no back pressure upon the steam hose. The valve handle (8') is now thrown forward parallel to 9 and the valve (22) closed. The course of the steam will therefore be direct through the pipes 7, 9, 11, 13, and may be directed against the snow or ice which it is desired to melt. The switch and switch levers being properly freed from the ice and snow, the valve (22) is now opened and the valve handle (8') turned to the position shown in Figs. 2 and 3. Steam will now be cut off from its direct passage and thrown through the by-pass 15, 18, 21, 23. In issuing from the reduced portion (20') of the nozzle (20), the steam will create a suction in the suction chamber (18). The attachment is now placed with the perforated member (19) below the surface of the water that is to be removed. Owing to the compact structure of the suction chamber and perforated member, we obtain an immediate priming and the water is now siphoned out through 21, 23, 12, and 13 and discharged at some place in which its freezing will not affect the switches or switch levers.

By providing the valve (22) we prevent any back current of steam when the attachment is employed for melting the ice. The shield (14) has been found desirable where the switch levers extending from the rails to the switch proper lie in a cinder depression, in that the cinders are prevented from flying

back against the operator. By providing our attachment with a by-pass and three-way valve for directing the steam either in its direct course or through the by-pass we have obviated all necessity of adjustment after the valve (3) has been opened to the requisite extent by the operator.

We claim—

1. In a locomotive attachment, the combination of apparatus for directing live steam against a frozen switch, with apparatus for siphoning water away from the switch levers, and means for rendering either apparatus inoperative during the operation of the other.

2. In a locomotive attachment, the combination of direct piping for throwing live steam against a frozen switch, with a by-pass on said piping for siphoning water, and means for cutting off the steam from the direct piping and sending it through the siphoning by-pass, as and for the purpose set forth.

3. In a locomotive attachment, the combination of direct piping, a by-pass leading from said piping adjacent to its end and re-connected with the piping toward the other end, siphoning apparatus located on the by-pass intermediate its ends, and means for closing either the by-pass or the piping adjacent the rear end of the latter, as and for the purpose set forth.

4. In a locomotive attachment, the combination of direct piping, a by-pass in said piping, siphoning apparatus located in said by-pass, and a three way valve located in the rear union of the piping and by-pass, as and for the purpose set forth.

5. In combination, a railway locomotive, pipes leading from the boiler and terminating at a plurality of points on the engine and tender, hand valves adjacent the termini of said pipes, an attachment comprising straight piping having a by-pass thereon, siphoning apparatus located in the by-pass, a steam hose connected to the piping, means for coupling the hose to a pipe terminus, and means on the attachment for directing steam through either the straight piping or the by-pass.

6. In an apparatus of the class described, the combination of a railway locomotive, piping leading from the locomotive boiler and terminating at a plurality of points on the engine and tender, with a member, adapted to be coupled to said piping for directing live steam against a frozen switch and having a shield thereon, as and for the purpose set forth.

7. In a locomotive attachment, the combination of piping, a by-pass thereon, a three-way valve at one end of the by-pass, a valve adjacent the other end, and siphoning apparatus in the by-pass and between said valves.

8. In a locomotive attachment, the combination of straight piping, a by-pass thereon, siphoning apparatus in the by-pass, said apparatus comprising a nozzle and suction chamber, having a perforated member secured thereto, and means for directing live steam through either the straight piping or by-pass.

In testimony whereof we affix our signatures in presence of two witnesses.
